UNITED STATES PATENT OFFICE.

WALTER HARRISON BIDDLE, OF LONDON, ENGLAND.

AUTOMATIC RAILWAY SIGNALING TRAIN CONTROL OR THE LIKE.

1,250,780.

Specification of Letters Patent. Patented Dec. 18, 1917.

Application filed August 8, 1916. Serial No. 113,822.

To all whom it may concern:

Be it known that I, WALTER HARRISON BIDDLE, a subject of the King of Great Britain, residing in London, England, have 5 invented certain new and useful Improvements in and Connected with Automatic Railway Signaling Train Controls or the like, of which the following is a specification.

10 In the specification of my prior application for patent filed 11 February 1916, Serial No. 77736 I have described means for automatically stopping a train or indicating to the driver when the line is blocked or the signals are at danger, and the present invention relates to an automatic railway signaling or train control system wherein apparatus such as described in the prior specification, or its equivalent is made use 15 of together with additional features.

This invention relates to automatic railway signaling or train control systems of the type in which a passing train is adapted to operate mechanism on the line which is 20 arranged to set other secondary mechanism at a suitable distance behind it designed to actuate a signal on a following train.

Means are well known for automatically stopping a train or indicating to the driver 25 when the line is blocked or the signals are at danger consisting of a tappet or like device on the train adapted to be operated by a stop or contact on the track adjustable according to whether the line is clear 30 or blocked.

The present invention is designed to utilize such means in a system of railway signaling which is wholly automatic and may be entirely independent of any manual control.

40 I have designed a train apparatus of the type described in which the tappet or operating device on the train is provided with a resilient contact member adapted to avoid fracture or shock on its operation by the 45 track stop and which forms the subject-matter of the concurrent application for patent, Serial No. 77,736, but in the present application I do not limit myself to the use of this apparatus.

50 In carrying out the invention there are arranged between or adjacent to the lines a series of tappets, levers, or other similar devices adapted to be engaged by a train as it passes, each tappet or lever corresponding 55 to a ramp or stop and being preferably set a short distance beyond same in the direc-

tion the train is going. Between the tappet and the ramp or stop means are provided whereby the operation of the tappet is caused to raise the ramp or stop or otherwise place it in position to stop a following train or produce a signal thereon.

Suitable means such as a spring catch, a pawl or the like are provided to retain the ramp or stop in the raised or operative 65 position.

In this way a train passing along periodically blocks the line behind it and so prevents another train overtaking it.

To lower the ramps or stops or place 70 them in inoperative position a second similar series of tappets, levers or the like to be engaged by the train are arranged along the line. Each tappet or lever as before corresponds to a ramp or stop, but in this 75 case they are generally set a considerable distance beyond the ramp in the direction the train is going, being preferably set beyond the next ramp so that the train always has a raised ramp behind it. In some cases, 80 it may be desirable to set such tappets two ramps or stops beyond the one to be made inoperative. These second tappets are preferably connected by suitable means to the 85 spring catch, pawl or the like of the corresponding ramp or stop in such a way that the operation of the tappets disengages the catch or pawl and allows the ramp or stop to take the inoperative position. An effective arrangement is to employ one tap- 90 pet for the combined purpose of setting the protective ramp or stop immediately 95 behind a train and for releasing a previously set ramp or stop further behind the train.

Similar tappets may be fixed at points or cross-overs and be arranged when a train passes over them to block the line the train is turning on to, or any cross-over lines and so prevent any other train foul- 100 ing the line along which the train has to pass. Or they may be employed to lock the points in such a way that no train can run onto a line along which the operating train is passing or is to pass.

The tappets, levers or the like may be of any suitable construction and may be operated by the engine in any convenient manner. They may, for instance, be arranged directly adjacent to the line and be operated by the flange or other part of the 110 wheels of the train as it passes along. Or

they may be arranged in any other position with regard to the lines and be operated by a shoe or the like carried by the engine or elsewhere on the train.

5 The tappets are preferably mounted on pivoted spindles and may be short so that the impact of the train gives them a sudden movement around their fulcra, or they may be made longer and arranged so that the 10 train operates them more gradually, or a short tappet may be arranged to be operated gradually by the intermediary of a longer arm or ramp adapted to be more gradually operated by the train.

15 The tappets are preferably inclosed or surrounded by a frame or box adapted to prevent snow, ballast or the like getting under them.

20 The tappets are preferably connected to their corresponding ramps or stops by means of wires, rods, chains or the like and springs or the like may, if desired, be inserted therein to take up any excessive jerk that may be imparted to it from the tappet.

25 Such a signaling or train control system may be employed independently of or in combination with an ordinary signaling system and will serve to automatically correct human errors or oversights in the latter. It is obvious that means may also be provided for operating ordinary signal arms or other indicators from the tappets, to provide a visual signal so that the driver may know beforehand if the line is clear 30 for him.

35 As stated above the invention involves the use of train apparatus for stopping the train or giving a signal on the train upon engagement with suitable track apparatus, such as is described in my prior application No. 77736 of 1916, or of equivalent apparatus, and such apparatus is not again illustrated herein, the drawings showing by way of example one form of permanent 40 way mechanism adapted to operate such train apparatus under the action of the train itself as it moves along, according to the invention.

45 Figure 1 is a plan showing an adjustable track stop with its setting and releasing mechanism.

50 Fig. 2 is an elevation of same showing the stop raised or set to engage the train apparatus.

55 Fig. 3 is a similar view showing the stop lowered or released.

60 Fig. 4 is an elevation of a tappet device adapted to be operated by the wheels of a train to set or release the stop operating mechanism.

Fig. 5 is a plan of same.

Fig. 6 is a plan showing a simple device for operating the stop mechanism simultaneously with the setting of points.

65 The stop A, see Figs. 1, 2 and 3, may be

of any suitable construction or form which is adapted to be raised or lowered as desired according as to whether the train apparatus of a passing train is to be engaged or operated or not. As shown the stop A comprises an arm rigidly mounted on a spindle *a* suitably pivoted in bearings *a'* mounted on a sleeper *a''* in such a manner that the arm or stop can be turned up or down respectively to engage or to avoid engagement 70 with the train apparatus. The upper end of the stop A may be formed as shown with a double inclined face so arranged that the two faces incline downward at opposite sides at approximately the same angle when the stop is raised, in the manner described in my said application No. 77736 of 1916, the object being to present a similarly inclined face to the train apparatus which ever way the train is traveling and to avoid 80 somewhat the suddenness of the shock which a flat face would produce.

Upon the spindle *a* is also mounted an arm *B* carrying a weight *b* adapted to rotate the spindle in such a manner as normally 90 to maintain the stop A in the lowered or inoperative position.

The spindle *a* also carries a second arm *C* for operating or rotating the spindle in the manner hereinafter described to raise 95 or set the stop A in position to engage the train apparatus.

To lock the stop A in the raised position there is mounted upon the spindle *a*, a disk *D* having a notch *d* formed in the periphery thereof adapted to receive a lug *e* formed on or carried by a pivoted and suitably weighted arm *E* or other suitable device. Normally the lug *e* rides or rests upon the periphery of the disk *D* (see Fig. 3) but when the stop A is raised it drops into the notch *d* (see Fig. 2) and holds the spindle and stop rigid against the action of the weighted lever *B* tending to turn the stop 100 downward out of the operative position. 110

To release the lug *e* from the notch *d* any suitable means may be provided for lifting the lever *E* so as to disengage them when it is no longer desired that any passing train should be engaged by the stop. For this purpose, for instance, a bell crank lever *F* as shown may be pivotally mounted upon an adjacent sleeper in such a manner that when one arm *f* of the lever *F* is pulled the other arm *f'* is raised and caused to engage the weighted arm *E* and lift it and so disengage the lug *e* from the notch *d*. The arm *f'* of the bell crank lever *F* may be weighted as shown if desired and said lever may be operated in the manner hereinafter 115 described. 120

At a suitable distance along the line beyond where each stop A is mounted is arranged a tappet or lever of suitable construction adapted to be engaged by a pass- 130

ing train to raise said stop A. A suitable form of tappet is shown in Figs. 4 and 5. In these views the tappet G consists of a curved lever rigidly mounted on a spindle g suitably pivoted in bearings g' on a sleeper g^2 , the tappet G being arranged immediately adjacent to one of the lines in position to be engaged and pressed down by the wheels of a passing train. The tappet is preferably curved as shown to permit of a train running in either direction operating thereon without difficulty.

Upon the spindle g is also mounted a weighted arm H adapted normally to maintain the tappet G in the raised position, and a second arm J which is adapted to be swung over when the tappet is depressed by a train passing over it. Attached at or near the end of the arm J is a wire, rod, or chain 20 or the like K, the other end of which is attached to the free end of the arm C of the stop mechanism of the corresponding stop A. It will therefore be seen that when the tappet B is depressed by a passing train and the arm J is swung over, the arm C of the stop mechanism will also be pulled over and the stop A raised till the lug e on the arm E drops into the notch d of the disk D when the stop will be locked in the raised position. 30 A spring or other elastic device may, if desired, be inserted in the wire or the like to take up any excessive jerk that may be imparted to it by the tappet and such device will also permit of extension of the wire 35 should the lug e enter the notch d before the lever J has finished its traverse. Such a device is shown in Figs. 4 and 5, where a spring K' is interposed between the connecting member K and the arm J, and a spring L' is interposed between the connecting member L and the arm J.

A similar tappet C placed farther along the line as hereinbefore described may also be employed for releasing or lowering the stop A by means of a wire or the like L connected from the arm J of the tappet spindle to the arm f of the bell crank F of the stop mechanism, or as shown in Figs. 4 and 5 one tappet may serve both purposes, that 45 is to say by means of a wire or the like K it may raise or set at a stop more or less immediately behind a train and by a second wire or the like L release or lower a stop a considerable distance behind it.

Fig. 6 shows an arrangement whereby the setting of suitable points may be caused automatically to block or clear one of a pair of converging tracks by means of stop apparatus as hereinbefore described. Suitably 50 pivoted, say upon a sleeper, is mounted a double armed lever M adapted to be rocked in one direction or the other on the setting of the points by means of the point rod N. For this purpose the rod N may be pivotally 60 connected to an arm m formed on the lever

M of such a length as to give the desired swing to the two arms of the lever M. To each end of the lever M is attached one end of a stop setting wire or the like K, each of which governs a stop on one of the converging tracks and also to each end of the lever M is attached one end of a stop releasing wire L connected to the same stop as the setting wire K at the other end of the lever M. It will be seen therefore that when the lever M is moved in one direction it raises or sets the stop A on one of the converging lines and releases the other and when it is moved in the other direction it has the contrary action, the stop which is set to block 70 the line of course always being that of the converging track other than the one along which the expected train is to be allowed to pass.

It is obvious that at a junction or cross-over by multiplying the connections K and L from such a lever M any number of tracks may be blocked and so trains thereon may be prevented from fouling the track which it is desired to leave clear.

It is also clear that with suitable and obvious modifications according to circumstances even the most difficult and complicated signaling or interlocking problems can be carried out according to the invention.

Having thus described the nature of the said invention and the best means I know of carrying the same into practical effect, I claim:

1. An automatic train control system comprising the combination of a track stop mounted on a pivoted spindle, a weighted lever adapted to rock the spindle to lower the stop, an arm on said spindle adapted to be operated from a distance by a passing train to turn it to raise the stop, locking means adapted to lock the spindle in position to hold the stop raised, and means for releasing said locking means.

2. An automatic train control system comprising the combination of a track stop mounted on a pivoted spindle, a weighted lever adapted to rock the spindle to lower the stop, an arm on said spindle adapted to be operated from a distance by a passing train to turn it to raise the stop, a disk upon the spindle having a recess or notch in its periphery, a pivoted lever having a lug adapted to enter said recess when the stop is raised to lock it in such position, and a second lever adapted to be operated from a distance by a passing train to raise the locking lever and permit the lowering of the stop.

3. An automatic train control system comprising the combination of a track stop mounted on a pivoted spindle, a weighted lever adapted to rock the spindle to lower the stop, an arm on said spindle adapted to be operated from a distance by a passing

train to turn it to raise the stop, locking means adapted to lock the spindle in position to hold the stop raised, means for releasing said locking means, a pivoted tappet or lever adapted to be engaged and rocked by a passing train, an arm adapted to rock with said tappet or lever, and means connecting said arm to an operating arm of the stop mechanism to raise or set it, or alter-
natively to a releasing arm of the stop mechanism, to lower or release it, or both to a setting arm of one stop mechanism and a releasing arm of another.

4. An automatic train control system comprising the combination with switch points, of a track stop mounted on a pivoted spindle, a weighted lever adapted to rock the spindle to lower the stop, an arm on said spindle adapted to be operated from a distance by a passing train to turn it to raise the stop, locking means adapted to lock the spindle in position to hold the stop raised, means for releasing said locking means, a double swing lever adapted to be rocked by the movement of the switch points, means connecting each end of said lever to the raising arm of one or more track stops and also to the lowering arm of the track stop or stops adapted to be raised from the other end of said levers.

3. An automatic train control system comprising the combination of a track stop mounted on a pivoted spindle, a weighted lever adapted to rock the spindle to lower the stop, an arm on said spindle adapted to be operated from a distance by a passing

train to turn it to raise the stop, a disk upon the spindle having a recess or notch in its periphery, a pivoted lever having a lug adapted to enter said recess when the stop is raised to lock it in such position, a second lever adapted to be operated from a distance by a passing train to raise the locking lever and permit the lowering of the stop, and means connecting the tappets or levers with the stop mechanisms. 45

6. An automatic train control system comprising the combination of a track stop mounted on a pivoted spindle, a weighted lever adapted to rock the spindle to lower the stop, an arm on said spindle adapted to be operated from a distance by a passing train to turn it to raise the stop, a disk on the spindle having a recess or notch in its periphery, a pivoted lever having a lug adapted to enter said recess when the stop is raised to lock it in such position, a second lever adapted to be operated from a distance by a passing train to raise the locking lever and permit lowering of the stop, and means connecting the tappets or levers with the stop mechanisms, said connecting means including an elastic device adapted to absorb any excessive jerk that may be imparted to it by the tappet.

In testimony whereof I have signed my name to this specification in the presence of two subscribing witnesses.

WALTER HARRISON BIDDLE.
